UNITED STATES PATENT OFFICE.

JOHN EDMUNDS, OF WALTHAM, MASSACHUSETTS.

CLOTH STRETCHER AND STRAIGHTENER.

1,203,719.

Specification of Letters Patent.

Patented Nov. 7, 1916.

Application filed October 8, 1915. Serial No. 54,781.

To all whom it may concern:
Be it known that I, JOHN EDMUNDS, a citizen of the United States, residing at Waltham, county of Middlesex, State of Massachusetts, have invented an Improvement in Cloth Stretchers and Straighteners, of which the following description, in connection with the accompanying drawing, is a specification, like characters on the drawing 10 representing like parts.

This invention relates to an apparatus for stretching and straightening cloth and it has for one of its objects to provide a novel apparatus of this nature which is so constructed 15 that it acts on the edges only of the web or cloth to be stretched and straightened, thus avoiding the disadvantages which are inherent in those machines which involve the use of calender or other rollers that have 20 contact with the cloth across its entire width. Where stretching or calendering rollers are used that do thus have contact with the cloth throughout the entire width of the latter it sometimes happens that the rollers 25 will either leave a mark on the cloth or that the contact of the rollers with the cloth will flatten down the surface of the cloth. My improved machine avoids this difficulty by using rollers which contact with the edges 30 only of the cloth.

Other objects of my invention are to provide a novel machine which can be used either separately as an independent machine or may be used in connection with drying 35 machines, or other machines used in the finishing of cloth.

Other objects of the invention are to provide a novel machine of this character by which the relative speed of movement of 40 the two edges of a fabric can be varied as it is fed through the machine and which is so constructed as to operate on different widths of cloth.

Other objects are to improve cloth-stretching and straightening machines, all as will be more fully hereinafter described and then pointed out in the appended claims.

In order to give an understanding of my invention I have illustrated in the drawings 50 a selected embodiment thereof which will now be described.

Referring to the drawings, Figure 1 is a plan view of a machine embodying my invention; Fig. 2 is an enlarged sectional view on the line 2—2, Fig. 1; Fig. 3 is a section on the line 3—3, Fig. 1; Fig. 4 is

a section on the line 4—4, Fig. 1; Fig. 5 is a diagrammatic view showing the way in which the rollers of my machine act on the cloth to stretch and straighten it; Fig. 6 60 is a fragmentary view showing one of the lower feed rolls and its supporting means.

My machine includes two pairs of cloth-feeding and stretching rollers adapted to engage the edges of the cloth to be stretched 65 and straightened, said rollers being set with their axes at an angle to the direction of movement of the cloth so that the action of the rollers will be to stretch the cloth. The machine also is provided with means for 70 varying the relative speed at which the rollers operate, thus providing for feeding one edge of the cloth faster or slower than the other, this construction being made use of to straighten the cloth and bring it into 75 a condition wherein the weft threads will extend at right angles to the length of the cloth. The machine is also constructed so that the two pairs of cloth-feeding and stretching rollers can be adjusted toward 80 and from each other thereby adapting the machine for use on different widths of cloth.

The cloth feeding and stretching rollers of one pair are designated 1 and 2, respectively, and those of the other pair are indicated at 3 and 4. All of these rollers are suitably mounted in a frame 5 which is herein constructed to present two upper cross members 6, the two lower cross members 7, and the end tie members 8 which 90 secure the cross members together. This frame 5 is supported on standards 9. Each of the rollers is journaled in a yoke which in turn is mounted in the frame 5 for turning movement about an axis perpendicular 95 to that about which the roller turns, thus providing for setting the rollers at the desired angular inclination. The lower rollers 2 and 4 are each journaled in a yoke 10 which is swiveled to a carrier or support 11 100 that is sustained on the lower frame members 7, said yokes being pivoted to the supports at 12. The upper rollers 1 and 3 are journaled in yokes 13, each of which has a stem 14 extending upwardly therefrom

that is mounted for turning movement in a support 15 that is mounted on the upper frame members 6. The axes of the stems 14 are in line with the pivots 12 so that the yokes of each pair of rollers turn about the 105 same axis.

The under rollers 2 and 4 of each pair con-

stitute the driving rollers and the upper rollers 1 and 3 constitute the presser rollers. Each driving roller 2 and 4 is driven from a pulley 16 fast on the shaft of the roller 5 and which is connected by a belt 17 to a driving roller or drum 18. These rollers 18 are mounted on shafts 19 which are journaled in the brackets 9 and the center bracket 20 respectively. The means for driving the 10 rollers 18 is such that the speed of rotation of said rollers can be varied relative to each other. As herein shown one shaft 19 is belted to a driving shaft 21 by means of a belt 22 and the other shaft 19 is belted to 15 the driving shaft 21 by means of another belt 23 which operates over the cone pulleys 24 and 25 on the shafts 19 and 21, respectively. The driving shaft 21 may be driven from any suitable source, such as a driving 20 pulley 26. The speed of rotation of the shaft 19 which is connected to the driving shaft 21 through the belt 22 has a fixed relation to the speed of the driving shaft 21, but the speed of rotation of the other shaft 25 19 can be varied relative to that of the driving shaft 21 by adjusting the belt 23 on the cone pulleys 24, 25. By this means the relative speed at which the driving rollers 2 and 4 are operated can be varied. The 30 purpose of this construction will be more fully set forth hereinafter.

27 indicates a table or rest over which the cloth is delivered to the rollers, this table or rest being suitably secured to the frame 5. 35 In order to effect the desired stretching of the cloth, the rollers are set so that their axes have an angular relation to the direction of movement of the cloth, as seen in the diagram Fig. 5, wherein 28 designates 40 the cloth which is moving in the direction of the arrow, and wherein the rollers are shown diagrammatically at 1 and 3. If the rollers are placed in the angular position shown in Fig. 5, the action of said rollers on the cloth 45 will be to draw the cloth through the rollers and at the same time to stretch the cloth, as will be obvious. The degree to which the cloth is stretched depends upon the angular position of the rollers, and my apparatus 50 55 provides means for adjusting the yokes 10 and 13 of the rollers so as to give the rollers any desired angular relation to the direction of the movement of the cloth. Each yoke has rigid therewith a segmental gear or rack 29 which is formed on the arc of a circle having as its center the axis about which the yokes turn. These racks mesh with pinions 30 carried by vertically-arranged shafts 31 and 32 that are suitably journaled in the 60 frame 5, each shaft having two pinions 30 thereon, one of which meshes with the rack 29 for the upper yoke 13 and the other of which meshes with the rack 29 for the lower yoke 10. By turning the shafts 31 and 32 65 the yokes will be turned about their axes

thereby changing the angular position of the axes of the rollers. The two shafts 31 and 32 are connected so that they may be operated in unison from a single point, thus insuring that both pairs of rollers will have 70 the same angular position. For this purpose each shaft 30 and 31 is provided at its lower end with a worm gear 33 which meshes with a worm 34 on a roller-adjusting shaft 35 which is journaled in suitable bearings 36 carried by the frame and is shown as provided with a hand-wheel 37 by which it may be operated. By this means the two pairs of rollers will be simultaneously adjusted and will always have the same angular relation to the direction of movement of the cloth. 75 80

As stated above, the upper rollers 1 and 3 are in the nature of presser rollers and the pressure is given to said rollers by 85 means of springs 40 situated within the stems 14 of the yokes 13 which are made hollow for this purpose. Each stem is mounted for sliding as well as turning movement in its support 15 and the spring 40 90 in each stem rests at its upper end against a nut 41 which is slidably mounted in the stem, but is held from rotation therein and which has screw-threaded engagement with a spindle or screw-threaded shaft 42 which is journaled in a bearing 43 carried by the frame 5, but is held from movement longitudinally thereof. By rotating the shaft 42 the nut 41 will be moved up or down thereby varying the tension of the spring 40 and thus varying the pressure of the rollers 1 and 3 against the cloth. I have provided herein means for simultaneously adjusting the tension of both springs 40, and for this purpose each spindle 42 has a bevel gear 44 fast thereon which meshes with a bevel pinion 45 on a shaft 46 mounted in suitable bearings 47 carried by the frame 5. This shaft 46 is provided with a hand-wheel 48 by which it may be operated. The tension of the springs 40 can thus be adjusted by simply turning the shaft 46 one way or the other. 95 100 105

In using the devices for stretching cloth, the cloth will be fed between the rollers and the angular position of the rollers will be adjusted by turning the shaft 35 so that the cloth will be stretched to the proper width as it is delivered from the machine. This angular adjustment of the rollers can be easily effected while the machine is in operation. 110 115 120

It sometimes happens that during the process of finishing cloth it becomes distorted so that the weft threads do not lie square across the cloth. This is illustrated in Fig. 5 wherein the weft threads are indicated by the lines *a* and *b*. The weft threads *a* extend in an inclined direction across the cloth and when the cloth becomes 125 130

distorted to produce this effect it is desirable that the cloth should be straightened so as to bring the weft threads square across the cloth. This straightening effect is here-
 5 in accomplished by causing the rollers of one pair to rotate faster than those of the other pair so as to cause one edge of the fabric to move faster than the other until the two edges have such relative positions that the
 10 weft threads extend square across the cloth. This adjustment of the relative speed of rotation of the rollers is accomplished by adjusting the belt 23 on the cone pulleys 24, 25 by means of the belt shipper 50. If in
 15 the operation of stretching the cloth the operator notices that the cloth as delivered from the machine is distorted so that the weft threads do not extend straight across the cloth, then he will shift the position of
 20 the belt 23 so as to cause one pair of rollers to rotate faster than the other, thus straightening the cloth. When the cloth becomes straightened he will again shift the belt 23 so as to cause the rollers of the two
 25 pairs to rotate at the same speed, thus maintaining the cloth in its straightened condition.

In order to adapt the machine for use on different widths of cloth, I have provided
 30 means whereby the two pairs of rollers can be adjusted toward and from each other. This is accomplished by making the upper supports 15 and also the lower supports 11 capable of adjustment toward and from each
 35 other. The supports 15 are slidably mounted between the upper frame members 6 and the supports 11 are slidably mounted between the lower frame members 7. The supports 15 are formed with the flanges 51 en-
 40 gaging the top and bottom of the frame members 6 and thus forming guides for the supports in their sliding movement. Similarly, the supports 11 are provided with flanges 52 engaging the top and bottom of
 45 the frame members 7 and acting as guides for the supports 11. Each support 15 has rigid therewith a nut or boss 61 which has screw-threaded engagement with a screw-threaded shaft 62 journaled in suitable bear-
 50 ings 63 carried by the frame. This shaft 62 is provided with right and left screw-threaded portions 75 and 76 so that as the shaft is turned the supports 15 will be moved toward or from each other. Each of the
 55 supports 11 has rigid therewith a nut or boss 64 which has screw-threaded engagement with a shaft 65 that is journaled in suitable bearings 66 carried by the frame. This shaft 65 is provided with the right and
 60 left screw-threaded portions 77 and 78 so that as it is turned the supports 11 will be moved toward and from each other. The shafts 62 and 65 are provided with bevel gears 67 and 68, respectively, that mesh with bevel gears 69 and 70 on a vertically-ex-

tending shaft 71 that is provided at its lower end with a hand-wheel 72 by which it may be operated. With this construction the pairs of rollers can be adjusted toward and from each other by simply turning the shaft 71 and thus the rollers can be adjusted to operate on cloth of any width. The driving rollers or drums 18 are elongated so that the belts 17 will have operative engagement therewith in any adjusted positions of the 75 pairs of rollers relative to each other.

It will be observed that the rollers have engagement with the cloth only at the edges thereof, and, therefore, the central or body portion of the cloth is not liable to become 80 injured or marked in any way by reason of its engagement with a stretching roller or straightening roller.

I claim:

1. In a machine for stretching and straightening cloth, the combination with two pairs of cloth-feeding and stretching rollers adapted to act on the edges of a web of cloth, of means for adjusting said pairs of rollers toward and from each other to 90 correspond to different widths of cloth, means for positively driving one roller of each pair, and means operative in any adjusted position of said pairs of rollers to vary the relative speed of the driven rollers. 95

2. In a device of the class described, the combination with two pairs of cloth-feeding and stretching rollers adapted to act on the edges of a web of cloth, of means to adjust the rollers of both pairs simultaneously 100 about an axis at right angles to the axis of the roller, and means operative in any adjusted position of the rollers for rotating the same.

3. In a device of the class described, the combination with two pairs of cloth-feeding and stretching rollers adapted to act on the edges of a web of cloth, of means to adjust said pairs of rollers toward and from each other to correspond to different widths of cloth, means for rotating said rollers, and means operative in any adjusted position of the rollers to adjust the rollers of both pairs simultaneously about an axis at right angles 105 to the axis of the rollers. 110

4. In a device of the class described, the combination with two pairs of cloth-feeding and stretching rollers adapted to act on the edges of a web of cloth, of means for positively driving one roller of each pair, means for varying the relative speed of the driven rollers, and means to adjust the rollers of both pairs simultaneously about an axis at right angles to the axis of the rollers. 120

5. In a device of the class described, the combination with two pairs of cloth-feeding and stretching rollers adapted to act on the edges of a web of cloth, of means for positively driving one roller of each pair, means for varying the relative speed of the driven 125 130

rollers, and means to adjust the rollers of both pairs simultaneously about axes at right angles to the axes of the rollers.

6. In a device of the class described, the combination with a frame, of two pairs of cloth feeding and stretching rollers, a yoke in which each roller is journaled, means for sustaining said yokes in said frame for turning movement about an axis at right angles to the axes of the roller, and means for turning all of said yokes simultaneously.

7. In a device of the class described, the combination with a frame, of two pairs of cloth-feeding and stretching rollers mounted in said frame, means for rotating one roller of each pair, means for adjusting the pairs of rollers toward and from each other, means operative in any adjusted position of the rollers for varying the relative speed of the driven rollers, and means to adjust both pairs of rollers simultaneously about an axis at right angles to the axis of the rollers.

8. In a device of the class described, the combination with a frame, of two pairs of cloth-feeding and stretching rollers mounted in said frame, means for rotating one roller of each pair, means for varying the relative speed of the driven rollers, means for adjusting the pairs of rollers toward and from each other, and means to adjust the rollers of both pairs simultaneously about an axis at right angles to the axis of the roller.

9. In a machine for stretching and straightening cloth, the combination with

two pairs of cloth-feeding and stretching rollers adapted to act on the edges of a web of cloth, of means for positively driving one roller of each pair, means for varying the relative speed of the driven rollers of the two pairs, and means for holding the rollers of each pair yieldingly pressed toward each other.

10. In a machine for stretching and straightening cloth, the combination with two pairs of cloth-feeding and stretching rollers adapted to act on the edges of a web of cloth, of means for positively driving one roller of each pair, means for varying the relative speed of the driven rollers of the two pairs, means for holding the rollers of each pair yieldingly pressed toward each other, and means to vary such yielding pressure.

11. In a machine for stretching and straightening cloth, the combination with two pairs of cloth-feeding and stretching rollers adapted to act on the edges of a web of cloth, of means for positively driving one roller of each pair, means for varying the relative speed of the driven rollers of the two pairs, means for holding the rollers of each pair yieldingly pressed toward each other, and means to adjust the rollers of both pairs simultaneously about an axis at right angles to the axis of the rollers.

In testimony whereof, I have signed my name to this specification.

JOHN EDMUND.
